Primary Examiner — Jonathan J Han*Assistant Examiner* — Amanda J Berlinski(74) *Attorney, Agent, or Firm* — Dragon Sun Law Firm, PC; Jinggao Li, Esq.; Nathaniel Perkins(57) **CLAIM**

The ornamental design for a nasal aspirator, as shown and described.

DESCRIPTION

FIG. 1 is a perspective view of a nasal aspirator showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is an enlarged top plan view thereof; and,

FIG. 7 is an enlarged bottom plan view thereof.

The broken lines shown in the figures depict portions of the nasal aspirator that form no part of the claimed design.

1 Claim, 7 Drawing Sheets(56)
